JAMES L. HAMILTON, OF GRAND JUNCTION, COLORADO, ASSIGNOR TO HAMILTON
ORCHARD HEATER COMPANY, OF WHEELING, WEST VIRGINIA, A CORPORATION
OF WEST VIRGINIA.

ORCHARD-HEATER.

1,126,453.

Specification of Letters Patent.

Patented Jan. 26, 1915.

Application filed February 7, 1914. Serial No. 817,102.

To all whom it may concern:

Be it known that I, JAMES L. HAMILTON, a citizen of the United States of America, and resident of Grand Junction, county of 5 Mesa, and State of Colorado, have invented certain new and useful Improvements in Orchard-Heaters, of which the following is a specification.

This invention relates broadly to orchard 10 heaters, and specifically to draft regulating means for such heaters.

The primary object of the invention is to provide a direct air passage to the stack from the usual damper-controlled opening 15 through which air is supplied to the interior of the fuel receptacle, whereby adjustment of the damper simultaneously accomplishes both regulation of the air supply to the receptacle and regulation of the air supply to 20 the stack.

A further object is to provide, in connection with an orchard heater wherein one or more depending draft tubes are employed for conducting air from a damper-controlled 25 opening to the surface of the oil, an auxiliary draft passage for conducting air directly from said opening to the stack, the air so conducted acting not only to increase the suction and thereby to facilitate combustion 30 of oil within the receptacle, but also to facilitate the combustion within the stack of gases arising from the burning oil.

With these other objects in view, the invention resides in the features of construction, arrangement of parts and combinations of elements which will hereinafter be exemplified, reference being had to the accompanying drawings, forming a part of this specification, in which—

40 Figure 1 is a top plan view of an orchard heater embodying my invention; Fig. 2 is a longitudinal section of the same on line 2—2, Fig. 1; Fig. 3 is a transverse section on the line 3—3, Fig. 1; and Figs. 4 and 5 are 45 sectional views similar to those shown in Figs. 2 and 3, respectively, illustrating a modification.

Referring to said drawings, in which like designating characters distinguish like parts 50 throughout the several views—1 indicates the fuel receptacle, and 2 a detachable cover therefor, said cover having a stack 3 mounted thereon, as ordinarily. Removably fitted within a suitable draft opening 4 provided 55 in the cover and which is controlled by a

suitable damper, as 5, is a draft tube 6 through which air is conducted into the receptacle for facilitating combustion of the oil, said tube preferably having one or more side openings, as 7, adapted to be gradually 60 uncovered as the fuel in the receptacle recedes.

Fixed to the under side of the cover 2 are the upturned lateral edges of a shallow sheet-metal trough 8 which has its front end 65 projected to a point inside the area encircled by the lower end of the stack and which extends rearward beyond the draft opening 4. An opening 9 which aligns vertically with said opening 4 is provided in said 70 trough for the accommodation of the draft tube 6, as shown in Figs. 2 and 3. A draft passage 10 is defined by said trough and the top of the cover, said passage being in open communication at its front end with the 75 lower end of the stack, and having communication at its rear end with the interior of the draft tube through one or more apertures, as the perforations 11, provided in the latter.

As is obvious, part of the air admitted through the damper-controlled opening 4 passes through the perforations 11 to the draft passage 10, through which it is conducted to the stack for facilitating combustion 80 of the gases arising from the burning oil in the receptacle. Adjustment of the damper 5 therefore accomplishes both the regulation of the volume of air admitted to the surface of the oil and of that supplied 85 to the stack through the passage 10, a single adjustment thus sufficing to regulate both supplies, which, as is apparent, correspondingly increase and decrease in a certain fixed ratio.

Referring now to the modification illustrated in Figs. 4 and 5, the draft tube is suspended from the bottom of the trough instead of from the cover, thus allowing direct communication between the opening 4 and 90 the passage 10 as well as between said opening and said draft tube. Here, too, a single adjustment regulates the volume of air admitted to the interior of the receptacle and that supplied to the stack.

Having thus described my invention, what I claim as new, and desire to secure by Letters Patent, is—

1. An orchard heater comprising an oil receptacle, a cover for said receptacle, a

stack mounted on said cover, a draft opening in the top of said cover, a trough attached to the under side of said cover intermediate the ends of the latter and having 5 communication at one end with said draft opening and at its opposite end with the interior of the stack whereby a draft passage is constituted, said trough having an opening therein adjacent to the draft opening 10 in the cover.

2. An orchard heater comprising an oil receptacle, a cover for said receptacle, a stack mounted on said cover, a draft opening in the top of said cover, a trough attached 15 to the under side of said cover intermediate the ends of the latter and having communication at one end with said draft opening and at its opposite end with the interior of the stack whereby a draft passage is constituted, said trough having an opening therein 20 adjacent to the draft opening in the cover, and means for regulating the volume of air admitted through said draft opening.

3. An orchard heater comprising an oil 25 receptacle, a cover for said receptacle, a stack mounted on said cover and communicating directly with said receptacle, said cover having a draft opening in the top thereof laterally of said stack, a trough attached 30 to the under side of said cover, said trough being in open communication at opposite ends with said draft opening and the interior of the stack and constituting a draft passage, and means for conducting air 35 to the interior of the receptacle.

4. An orchard heater comprising an oil receptacle, a cover therefor, a stack mounted on said cover and communicating through the latter directly with the interior 40 of said receptacle, adjustable means supplying air to said receptacle, and means permanently attached to said cover for diverting part of said air supply directly to the lower end of said stack.

45 5. An orchard heater comprising an oil receptacle, a cover therefor, a stack mounted on said cover and communicating through the latter with the interior of said receptacle, said cover being provided with 50 a draft opening therein at a point laterally of the stack, through which air is supplied to the interior of the receptacle, a trough mounted on the under side of said cover and having communication with said draft opening, said trough also communicating 55 with said stack and constituting a draft passage between said opening and said stack, and adjustable means for regulating the draft through said opening.

60 6. An orchard heater comprising an oil receptacle, a cover therefor, a stack mounted on said cover and communicating through the latter with the interior of said

receptacle, a damper-controlled opening in 65 said cover for supplying air to the interior of the receptacle, and means attached to said cover for conducting a portion of the air admitted through said opening directly to the lower end of the stack.

7. An orchard heater comprising an oil 70 receptacle, a cover therefor, a stack mounted on said cover and communicating through the latter with the interior of said receptacle, a damper-controlled opening in 75 said cover for supplying air to the interior of the receptacle, and a trough disposed in fixed relation to said cover and constituting a passage through which a portion of the air admitted through said opening is diverted directly to the lower end of the stack. 80

8. An orchard heater comprising an oil receptacle, a cover therefor, a stack mounted on said cover, a trough disposed on the under side of said cover to form a draft 85 passage, said passage being in open communication at one end with the lower end of said stack, vertically aligned openings provided in said cover and said trough, a draft tube projected into the receptacle through said openings, and having apertures 90 therein through which air is admitted to said passage, and means for regulating the volume of air admitted to said tube.

9. An orchard heater comprising an oil 95 receptacle, a cover therefor, a stack mounted on said cover, a trough disposed on the under side of said cover to form a draft passage, said passage being in open communication at one end with the lower end 100 of said stack, vertically aligned openings provided in said cover and said trough, a draft tube projected into the receptacle through said openings and suspended from said cover, said tube having apertures 105 therein through which air is admitted to said passage, and an adjustable damper for regulating the volume of air admitted to said tube.

10. In an orchard heater, the combination 110 with a receptacle cover having a stack mounted thereon and a draft opening therein, of a trough fixed on the under side of said cover and having communication at opposite ends with said opening and said stack and constituting a passage through 115 which a portion of the air admitted through the former is conducted directly to the latter.

In testimony whereof, I affix my signature in presence of two subscribing witnesses. 120
